UNITED STATES PATENT OFFICE.

GEORGE WASHINGTON WOOLLEY, OF WASHINGTON, D. C.

DETACHABLE RESERVOIR FOR PENS.

SPECIFICATION forming part of Letters Patent No. 299,499, dated May 27, 1884.

Application filed October 25, 1883. (No model.)

To all whom it may concern:

Be it known that I, GEORGE WASHINGTON WOOLLEY, a citizen of the United States, residing at Washington, District of Columbia, have made Improvements on Reservoir Attachments for Pens; and I hereby declare that the following is a full and accurate description thereof, reference being made to the accompanying drawings, and to the letters and figures marked thereon.

I construct a shank to the reservoir, which, being applied to the pen's concavity and inserted with it into the holder, will be held in it securely, and, being made of durable material, it lasts for many years, and is convenient and desirable for use in penmanship and drawing for many reasons, among which are the following: It fills as quickly with the pen as the pen does without it by dipping. It is applicable to the common pen—steel or gold—does not affect the pen's elasticity or fineness, and increases the pen's capacity for writing from a single dip twenty to fifty times, by writing a page or several pages of cap paper, according to the size of the reservoir and the number of its tongues or valves.

My improvements are described hereinafter, and particularly pointed out in the claims.

In the drawings, Figure 1 represents a pen with its concavity exposed and the ink-holding reservoir placed in position. Fig. 2 is a bottom view of the reservoir having a single valve; Fig. 3, a longitudinal section of the reservoir provided with a series of valves, and Fig. 4 a bottom view of the reservoir without a valve.

In Fig. 1 the reservoir *c* is shown in the pen *a* ready to be inserted into the holder, its point being within about an eighth of an inch of the point of the pen, its shank *b* extending to about the upper end of the pen. It will be seen that there is a perforation or air-duct, *o*, in the upper end of the body of the reservoir, and also one, *e*, near it in the shank. These are for the transmission of air from and into the reservoir, which facilitates its filling in dipping and its shedding ink freely when in use.

In Fig. 2 the reservoir is of medium size, with a single valve or tongue, *d*, extending from the air-duct at *o* to within about an

eighth of an inch of the point of the reservoir. At about the same distance is a slight niche or excavation, *g*, extending to its point. This excavation is made by cutting back from the point of the reservoir on its under surface about an eighth of an inch, as clearly shown at *h*, or what may answer the same purpose, by leaving a little rotundity of the edge of the sides back of that point. The object of this cut-away portion is to prevent the reservoir for about an eighth of an inch back from the point from pressing against the pen, in order that the action of the reservoir and pen may not be impaired. This feature greatly facilitates the free flow of ink from the pen, as well as filling the pen and reservoir in dipping, prevents clogging, and at the same time prevents the attachment from impairing the proper function of the pen's nib.

When the reservoir is furnished with a tongue or valve, it should be made of alloyed gold or other elastic material, so that its free end shall always spring against the pen, and not adhere to the bottom of the reservoir, nor touch its sides.

In Fig. 3 is shown the largest reservoir, containing four valves, the end of the longest extending to about an eighth of an inch of the point of the reservoir, and the other three successively about an eighth of an inch shorter, being soldered near the upper portion of the reservoir, as seen in the drawings. This large four-tongued or valved reservoir is for the largest gold or steel pens, that may be carried in a case with a dip of ink in an air-tight holder during a day or night, and will write a page or two of cap paper, if required, without redipping.

In Fig. 4 the reservoir is without a tongue or valve, but has the perforation in the reservoir and shank with a crevice between them, which may be useful in some cases by increasing the transmission of air.

What I claim is—

1. An ink-holding attachment for pens, consisting of a reservoir and a shank, each provided with an air-opening near the upper end of the bulb of the reservoir, substantially as set forth.

2. The ink-holding attachment for writing

and drawing pens, consisting of a reservoir and a shank, and provided with an air-duct in the former and an under-cut at and near the point, substantially as and for the purpose set forth.

5 3. The ink-holding attachment for writing and drawing pens, consisting of a reservoir and a shank, the former provided with a cut-away portion, *g*, at and near its point, substantially as and for the purpose set forth.

10 4. The ink-holding attachment for writing

and drawing pens, consisting of a reservoir and a shank, and provided with an air-transmission duct, and cut-away portion *g* at and near the point, as set forth, combined with a tongue or valve, *d*, substantially as described and 15 shown.

GEORGE WASHINGTON WOOLLEY.
